UNITED STATES PATENT OFFICE

MURRAY J. MARRITS, OF NEW YORK, N. Y.

COLLAPSIBLE DISPLAY STAND

Application filed December 18, 1928. Serial No. 326,719.

My invention relates to stands of the type used in grocery and other stores for the display of goods in package form, i. e., goods put up in cans, cartons and the like. It is the usual custom to display such goods by placing them loosely on shelving, stands, or in stacked relation. When so supported, the owner is subjected to more or less loss from theft of the goods, which is particularly heavy in those instances where the goods are displayed in the front of stores or in open spaces in the stores readily accessible to the public. Furthermore, when the goods are displayed in the loose form referred to, particularly when in stacked relation, they are liable to fall when pushed against, in which event the packages are subject to damage, through breakage, or other injury such as denting of the cans, with consequent loss to the owner.

With the foregoing in mind, it has been the object of my invention to provide an improved display stand by means of which packaged goods in any desired quantities may be openly displayed in stack form without liability of loss from theft or otherwise. This object I attain by means of the improved stand hereinafter described and claimed and which is illustrated in the accompanying drawings, in which—

Figure 1 is a front elevation of a display stand embodying my invention having a quantity of canned goods mounted thereon in stacked relation.

Figs. 2 and 3 are top and side views respectively, of the same.

Fig. 4 is an enlarged sectional detail showing the flanged construction of the lower or base plate of the stand and the connection therewith of the standard with which the several package supporting and holding plates of the stand connect.

Fig. 5 is an enlarged end view of one of the package supporting plates, showing an adjustable feature of same.

Fig. 6 is a section through the same plate looking in the opposite direction from that of Fig. 5.

Fig. 7 is a sectional elevation of the stand in a somewhat modified form, and

Fig. 8 is a top plan view of the same.

The stand, in the form shown in Figs. 1 to 6 inclusive, comprises a plurality of package supporting plates, such as 1, 2, 3 and 4, which may vary in size and number to meet different requirements and which are held in superimposed relation by connection with a vertical standard 5 at the rear side thereof, the connection of the plates with said standard being a loose one to permit of their spacing or adjustment relatively to each other according to the height of the packages to be supported thereon.

Each of the supporting plates is provided at its outer edge with an upturned flange or rib, such as 6, for engaging with the lower edges of the packages on the plate to retain them against horizontal displacement thereon. Each of the plates is also divided lengthwise thereof, as at 7, to permit of their adjustment in a transverse direction whereby to adapt them to packages of different sizes. Any suitable means may be employed to secure the plate sections in their adjusted relation, the means here shown comprising a fastening strip 8 at each end of the plate adapted for adjustable connection with the end flanges thereof by means of screws or bolts 9 passing through openings 10 and 11 in the fastening strip and plate flanges respectively, as most clearly shown in Figs. 5 and 6. With such means it will be clear that the plates may be readily adjusted to adapt them for packages of different sizes, and when the sections comprising each of the same are spaced apart, the fastening strips or plates 8 serve to bridge the space between the adjacent ends of the separated flanges 6, as shown in Figs. 5 and 6.

In the use of my improved stand as illustrated in Figs. 1 to 6 inclusive, a row of cans 11, here shown as four in number, are placed on the bottom or base plate 1. A second plate 2 is then positioned to rest upon the top of these cans. If the cans are to be stacked in pyramid form as shown, this second plate 2 will preferably be of less length than the lower one but in any event will be of sufficient length to partially overlie all of the cans of the first row or tier as shown. Further rows will then be stacked on the additional plates

3 and 4 in the same way until the top is reached as shown.

The several plates, 1, 2, 3 and 4, as hereinbefore referred to, are held in superimposed relation by connection with a standard 5, which latter has a fixed connection with the base plate, here shown (see Fig. 4) as a screw-threaded connection with a socket piece 15 at the rear side of said plate. The connection of the other plates with this standard is a sliding one and is effected by means of a perforated extension 16 at the rear of each through which the standard loosely extends. With such loose or sliding connection of the plates with the standard, they are readily adjusted to the different heights of the cans or packages being stacked and so permit of the ready and compact stacking of the same.

20 After stacking of the cans in the way described, they are next secured against removal from their supporting plates by means of a fastening cap or plate 17 carried by the standard and engaging with the upper side of the top can, this fastening plate cooperating with the base plate to hold the interposed rows of cans and their supporting plates against vertical movement relatively to each other and thereby securing the cans 25 against removal from their supporting plates in a horizontal direction through the engagement therewith of the retaining side flanges 6.

After the cans have been thus stacked and secured, the only way of removing them from the stand without loosening up or removal of the cap plate 17 is to swing any of the plates in a horizontal direction about the standard 5 and thereby expose the underlying can or cans. This would be difficult to accomplish because of the friction between the parts, particularly if the cap plate 17 was secured down tightly, but in order to prevent possibility of such horizontal movement of the plates, each of the same above the base plate is provided with downwardly projecting lugs, such as 18, at their front and rear edges, which engage the upper ends of the immediately underlying cans, as shown in Figs. 1 and 2, and thereby lock the plates against horizontal movement such as referred to.

The cap plate 17 may be adjustably connected with the standard in any suitable way. 55 As here shown, it is carried by the horizontal arm 20 of a rod 21 slidably fitted within the upper tubular end of the standard 5 in which it is held for vertical adjustment by means of an engaging set-screw 22 mounted in the head of the standard. During stacking of the cans, the plate 17 may be raised or swung laterally out of the way, but after the stacking is completed said plate is brought down tightly against the upper side of the top can to thereby lock the several rows together as

a single unit, after which it is secured in such position by tightening the set-screw 22. As a means of positioning the fastening plate 17 horizontally with respect to the stack, it has a sliding connection with its supporting arm by means of a horizontally perforated block 23 thereon which receives said arm there-through. A set-screw 24 in said head engaging with the arm serves as a means to secure the plate in adjusted position on the latter.

As a means for carrying a display card for price or other indicia, the plate 17 is provided with a suitable holder 25 therefor, which is preferably mounted on the upper side of the block 23 thereon. With the card holder thus supported, it is always in position at the top of the stack irrespective of the height or form of the latter.

Referring now to Figs. 7 and 8, these show the stand adapted for a three tier stack instead of a four tier stack as in Figs. 1 to 4 inclusive, the only difference as to such feature being the elimination of one of the supporting plates. These figures also show the supporting plates drawn apart for the support of larger packages than those in Figs. 1 to 4 inclusive, in which latter the plates are shown as adjusted to their minimum width with their adjacent longitudinal edges abut-

ting. In Figs. 1 and 6, the supporting plates above the base, as hereinbefore described, have a loose sliding connection with the standard 5 and are held down to their position of holding engagement with the top of the underlying packages by means of the top or cap plate 17. In some instances I prefer to connect these plates with the standard by a screw-threaded connection, as shown at 30 in Fig. 7, whereby, when turned down against the tops of the immediately underlying packages, they will act to retain the latter in position on their supports independently of the cap plate, the latter in such case serving only to hold the top can or tier of cans in position.

In stacking cans in loose form as ordinarily practiced, it is customary to start with a double or triple row as a base on which to stack the upper rows, in order to give the stack as a whole the necessary stability to maintain it against collapsing when subjected to any slight jarring or pushing. With my improved stand this is not necessary, as the interlocking of the several rows or tiers together as a single unit permits them to be laid up or stacked in single rows, and further, after being so stacked, to be readily moved about as desired without any taking down or unstacking of the same.

What I claim is:

1. A collapsible display stand, comprising a sectional base plate having flanges for holding engagement with the sides of packages

placed thereon, the sections of said plate being adjustable relatively to each other in a direction to vary the size of its package receiving area, means adjustably connecting 5 the flanges of said sections for securing the latter in adjusted position, a top plate for holding the packages from the upper side thereof, and means for securing the top and base plates in fixed relation.

10 2. A collapsible display stand, comprising a sectional base plate having flanges for holding engagement with the sides of packages placed thereon, the sections of said plate being adjustable relatively to each other in a 15 direction to vary the size of its package receiving area, fastening strips overlying the adjacent ends of the flanges at their points of division, means for adjustably fastening said strips to the flanges for securing the sections 20 in adjusted position, a top plate for holding the packages from the upper side thereof, and means for securing the top and base plates in fixed relation.

In testimony whereof I affix my signature.
